UNITED STATES PATENT OFFICE.

JAMES R. MCWANE, OF BIRMINGHAM, ALABAMA.

PIPE-FOUNDRY PLANT.

Application filed May 12, 1923. Serial No. 638,639.

To all whom it may concern:

Be it known that I, JAMES R. MCWANE, a citizen of the United States, residing at Birmingham, in the county of Jefferson and State of Alabama, have invented new and useful Improvements in Pipe-Foundry Plants, of which the following is a specification.

This invention relates to improvements in pipe foundry plants.

The object is to simplify and to expedite the manufacture of cast iron pipe by the horizontal method wherein the excessive handling of the core bars, cores, and flask sections is reduced, the casting being done in horizontal molds upon the ground or floor of the foundry, and without employing a pit as in the vertical method of molding which is highly expensive to operate as well as dangerous to the operatives.

Another object is to adapt the various improved means in general use in the production of cast iron pipe by the horizontal casting method, such as the core machine for making the necessary cores, and the molding machine for forming the molds in the cope and drag sections comprising the flasks, so as to make practicable the manufacture of pipes of greater lengths than has heretofore been possible by the horizontal method of casting.

A further object is to provide for a more condensed and convenient arrangement of the necessary machines and devices used in horizontal pipe casting, with relation to the cupola, and the required lifting and conveying means in the form of traveling cranes having transversely-movable carriers, and independent hoists for handling the pouring ladle, the flask sections and the cores respectively, such novel arrangement enabling these elements to be placed in position and manipulated expeditiously and with the minimum amount of handling, and without the danger usually attendant upon such operations, thus resulting in the saving of a great amount of time and a consequent reduction in the cost of production by the employment of fewer operatives.

A still further object is to arrange the plant or foundry in the form of a series of units or sections, known as "bays", each being independent of the others and capable of making pipe, and having the flasks with the molds formed therein, in a position to facilitate the pouring of molten metal from

a single, elongated, multiple-lipped ladle, which may receive its charge from a cupola capable of serving one or more of said "bays", the said ladle being shiftable without danger of accidental tilting from one end of the "bay" to the other for pouring into any one of the molds, and capable of being shifted from the overhead carrier or crane to a transfer car movable laterally of the "bays" to position the ladle before the cupola for receiving its charge.

A full and complete understanding of the invention may be obtained from a consideration of the following detailed description, taken in connection with the accompanying drawings forming a part of this specification; it being understood that while the drawings show practical forms and arrangements of the invention, the latter is not confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:

Fig. 1 is a diagrammatic showing, in plan view, of the arrangement of a plant in accordance with the invention.

Fig. 2 is an enlarged, transverse section through two of the units or "bays" and showing different steps in the operation of making cast iron pipe by the improved method.

Fig. 3 is an enlarged, longitudinal section through one end of a unit or "bay" and showing its relation to the cupola and the transfer car.

Fig. 4 is a plan view of the multiple-lipped ladle used in the pouring of the molten metal.

Fig. 5 is a plan view of the flask, with the mold therein.

Fig. 6 is a plan view, similar to Fig. 1, and showing a modified arrangement of the "bays" with relation to the cupola.

The foundry plant illustrated in Fig. 1 of the drawings comprises a plurality of units or sections defined by and arranged between the upright posts or I-beams forming part of the structure of the housing of the plant. Such sections are known in the art as "bays", and may be of any desired number and arranged, in this form of

the invention, side by side, and the same may have any desired dimensions, and said "bays" are each independent of the other and capable of making cast iron pipe or other castings, except that for convenience, two or more "bays" may be served by one cupola and one core machine.

Each "bay" is equipped with two pairs of spaced rails constituting longitudinal service tracks 2 for a molding machine 3, said tracks 2 being located adjacent to the posts 1 on each side, and suitably set in the ground or floor to withstand the weight of the said molding machine, which latter may be of any desired form capable of receiving the cope and drag sections comprising the flask, for the purpose of making the mold in the same.

The tracks 2 extend from what may be termed the front end of each "bay" to a point somewhat beyond the longitudinal center of the same, and the inner, opposed rails thereof are flanked by longitudinally-disposed sills 4, which may be formed of wood, metal or concrete, the upper surfaces of the same being elevated slightly above the floor level and stopping, at their inner ends, short of the ends of the tracks 2.

Midway between the sills 4 is a central, longitudinally-disposed sill or support 5 formed and set similarly to the supports 4 and extending towards the center of the "bay" a distance equal to said sills 4, the latter comprising supports for the ends of flasks 6, which are placed thereon transversely of the "bay", and the center sill 5 serving to chock up the center of said flasks as by means of a wedge 7, shown in Fig. 2 of the drawings.

Beyond the inner ends of the tracks 2 and spaced therefrom, is another track 8 of wider gage than the same and located at the center of the "bay" and extending rearwardly to the rear end of the same, said track comprising rails somewhat elevated above the ground level and adapted to receive empty core bars 9, which latter may be of any desired form capable of having a sand core made thereon.

At each side of the rear, central track 8 are other tracks 10, in spaced relation thereto and located adjacent to the line of posts 1 defining the walls of the "bay", and adapted to receive, transversely thereof, finished pipes 11 both before the core bars 9 have been withdrawn therefrom and afterwards to allow the latter to be rolled to the rear end of the "bay".

The molding machines 3 mounted to run on the tracks 2 may be adapted for hand ramming or for mechanical ramming, and are moved along to any position, opposite to the point of operations; and arranged between the posts or columns 1 and the adjacent tracks 2 are stacks 12 of flask sections

or members, each stack preferably consisting of an equal number of copes and drags. The copes 13 are preferably placed at the bottom of the stacks and telescoped on one another, and the drags 14 which are similarly constructed, are inverted and placed in telescoped relation on top of the copes as indicated in the right hand "bay" of Fig. 2, which is a transverse sectional view looking toward the inner end of said "bay".

The stacks 12 are arranged longitudinally of the "bay" and in slightly spaced relation, there being sufficient cope and drag sections in said stacks on either side of the "bay" to form a continuous series of flasks 6, in parallel relation and transversely of the "bay", and resting upon the sills 4, such arrangement resulting in great economy of space within the foundry or plant.

Between the center sill 5 and the opposite sills 4 there is heaped molding sand 15, preferably in two piles extending the full length of the said sills and adapted to be shoveled into the cope and drag sections, after the latter have been placed in the molding machines 3 and the proper pattern positioned therein, when the same is rammed either by hand or mechanically.

The posts or columns 1 support overhead tracks 16, one at each side of each "bay", and mounted on said tracks is an overhead traveling crane 17 movable longitudinally of the "bay" a distance substantially equal to the length of the floor tracks 2. This crane 17 carries a smaller, transversely-movable carriage 18 having a hoisting means and connections, including a spreader bar 18^a for attachment to the ends of the cope and drag sections, for the purpose of handling the same either longitudinally or transversely of the "bay", to place them on the molding machines, and then upon the sills 4, after the mold impressions have been made therein by the said machines; it being understood that the drags are first placed and then the copes on top of the same to comprise the flasks.

The crane 17 is also provided with spaced hoists 19 wound upon a winding drum 20 connected to a motor 21 under control of the crane operator, said hoists including hooks 22 for engagement with eyes 23 carried on trunnions at each end of an elongated ladle 24, said ladle being substantially equal in length to the lengths of the flasks, and provided with a series of pouring lips 25, and steadyng and guiding handles 26 at one end, while at the other end, the ladle is provided with suitable worm gearing suitably encased, as at 27, and having an operating hand-wheel 28, for the purpose of properly tilting the ladle when pouring the molten metal therefrom.

The ladle 24 is preferably mounted upon a central, vertical pivot carried by the sup-

plemental car 38, so that the said ladle may be turned slightly in one direction or the other while beneath the spout 37 of the cupola, in order that the flow of the molten metal therefrom may be directed more or less longitudinally of the ladle to prevent spilling or splashing of said metal, as the flow fluctuates considerably depending upon the head of the metal which, when the cupola is full, flows forcefully and when the supply in the cupola decreases, flows with diminished force.

Arranged centrally and longitudinally of each "bay" is a monorail 29 suitably supported by the roof trusses of the "bay", and the ends of two adjacent monorails may be joined by a loop 29^a so as to connect one "bay" with another, when it becomes desirable to carry from one to the other. Mounted on each monorail is a trolley 30 capable of being shifted along the same, and provided with hoisting means and connections including a spreader bar 31^a, for handling the core bars 9, both before and after the cores have been made thereon by the core machines 31. The core machines may be of any form capable of making the cores upon the bars 9, and are preferably placed transversely of the "bays", there being one machine located in line with every alternate line of columns or posts 1, so that one machine will serve for two adjacent "bays", the inner or rear loops 29^a passing adjacent to the said machine to receive the finished cores therefrom, and to convey the same to the flasks 6 wherever the latter may be situated along the rails 2.

The trolley hoists 30 are equipped with detachable operating bars or levers 32 for controlling the hoisting mechanism thereof, and the same may be removed when it is desired to pass the main crane 17 as shown at the left hand side of Fig. 2.

At the rear or inner loop 29^a of the monorails 29, branch rails 29^b are provided to which the trolleys may be transferred by suitable switches, and said rails 29^b extend rearwardly for a distance beyond the core machines 31, where they are directed inwardly and joined to a single, central, longitudinal monorail 29^c, extending to the rear end of every alternate "bay", for the purpose of carrying finished pipe 11, with the core bars 9 therein, to a position adjacent to transversely disposed core bar pulling machines 33, which act to draw the bars from said pipe.

The trolley hoist is thus employed to lift and to carry the completed cores from the machines 31 and place them in the drag sections upon the sills 4 before the cope sections are placed in position thereon, and it is also employed for carrying the completed pipe containing the core bars and cores to a common point indicated at A (Fig. 1),

preparatory to drawing the bars by the machines 33, which are placed in a staggered relation to permit of their operation.

The overhead tracks 16 extend, at the cupola end of each "bay", to a point over a transfer track 34 arranged on the floor level and at right-angles to the ends of the "bays", and the track 34 carries a transfer car 35 which is adapted to be moved along in front of any one of the same, and in a position before a cupola 36 having a spout 37 in overhanging relation to the car 35. Mounted on the car 35 is a smaller, supplemental car 38 movable transversely of the main car, and having means for supporting the elongated, multiple-lipped ladle 24 beneath the spout of the cupola to receive a charge of molten metal, the said ladle being adjusted in proper position by means of the desired amount of movement of the car 35 longitudinally of the ladle or movement of the car 38 transversely of the said ladle. (Fig. 3).

With the ladle mounted on the supplemental car 38 and filled with metal, the car 38 is first shifted away from the spout of the cupola, and thence shifted by the main car to a position at the end of the desired "bay", the said ladle being then beneath the overhanging ends of the longitudinal tracks 16, which extend almost across the floor tracks 34 and in a position to have the hoists 19 of the overhead, traveling crane 17, connected thereto by means of the eyes 23 and the hooks 22, when the ladle may be carried to any point along the "bay", it being preferable to start pouring the mold in the flask 6 farthest removed from the cupola.

The cycle of operations is as follows.— The molding machines 3 are moved along the tracks 2 to the starting point indicated at B in Fig. 1, the two machines in a single "bay" being located opposite each other. The crane 17 is shifted to the longitudinal stack of flask sections 12 adjacent to said machines, and the uppermost drag section 14 on one stack 12 is picked up by the transversely movable hoist 18, through the spreader 18^a and placed on one of the machines 3. While this drag section is being filled with sand from the heaps 15 and rammed around the proper pattern in any desired manner, the hoist 18 with the spreader 18^a, is moved over to the opposite molding machine 3 and picks up another drag section 14 from the adjacent stack 12, and places the same on said machine. Then the crane moves back to the first machine and picks up the rammed drag therefrom and conveys it to the first flask location at the inner ends of the sills 4, the said drag being inverted and turned at right angles so that its ends may rest upon said sills. The crane returns to the first stack of cope

and drag sections and picks up another drag, placing the same on the first machine 3. By this time the opposite drag has been rammed in the second machine 3, 5 and the hoist 18 is moved across and picks up the drag from this machine and places it, after inversion, alongside of the first drag section upon the sills 4. This alternate serving of the two machines 3 in a 10 "bay" is continued until all the drag sections 14, in two of the opposite stacks 6, have been rammed and placed in position transversely of the "bay"; and while such operation is taking place, the monorail 15 hoist 30 begins to bring cores formed by the core machine 31 on the core bars 9, and places the same in position in the drags, having one-half of the mold formed therein. As soon as a number of cores have 20 been placed in position in the drags, the overhead crane 17 begins picking up the cope sections 18, which have been uncovered by the removal of the drag sections, and places the same on the machines 3, alternately, for ramming, and then, when 25 rammed, placing the copes in final position on the drags, with the cores properly positioned therein, ready for the casting of the metal from the multiple-lipped ladle 24, 30 the upper faces of the sand in the cope sections being provided with a suitable gate for each pouring spout 25 of the ladle. This ramming and placing of copes and drags is continued until the entire series 35 of opposite stacks 6 of drag and cope sections is exhausted.

The machines 3 are then moved forward to a new location, where there are additional stacks of flask sections, and an additional 40 supply of sand, and the operations described above are repeated over and over, at each new location of the machine, until the entire supply of flasks has been used and the entire floor of the "bay", between the tracks 2, is filled with molds ready for 45 pouring, except the space between the machines in their last location, indicated at C in the drawing, Fig. 1.

After the flasks have been clamped and 50 wedged up at their centers on the sill 5, they are ready for casting, and the crane 17 is moved to the extreme end of the crane tracks or runways 16 where overhanging the transfer car tracks 34. The crane picks 55 up the ladle from the transfer car, after the same has been shifted into position by the supplemental car 38 from before the spout of the cupola, and said transfer car has carried the ladle to a point beneath the 60 crane, when the latter moves along the "bay" to the mold at the end of the crane runway where the first pouring takes place, the latter operation continuing from one mold to the next adjacent one until all of 65 the metal is poured and the ladle returned

to the cupola for re-filling. The simultaneous lifting of the ladle at both ends and elevating the same by cables having a common speed of travel, instead of by the usual, single bail having a single point of 70 suspension at the center of said ladle, prevents the tilting of the same and the consequent surging of the molten metal from end to end of the elongated ladle, and thus it may be transported with safety and the 75 pipe cast quickly, the metal entering the mold through a plurality of gates and insuring a proper casting. The ladle is repeatedly re-filled until all of the molds have 80 been poured, and by the time the last of the molds have been reached for pouring, the first of the molds may have cooled sufficiently to open the flasks and remove the pipe therefrom.

The crane now picks up the copes, after 85 the same have been unclamped from the drags, and elevates them one at a time, the sand being rapped out while the cope is suspended from the spreader 18^a, said sand thus falling in a position to be heaped 90 again, without undue shoveling, between the tracks 2. A number of the copes are thus freed from the sand, and they are again stacked on each side as before, and the crane 95 then, through said spreader 18^a, is attached to the trunnions of the drag sections, which are so arranged as to permit of the drag being inverted, so as to drop the sand therein on the floor together with the pipe with the core therein. The sand is now rapped out 100 of the drags, and they are stacked in inverted position on top of the stacked copes, and this alternate handling of the cope and drag sections continues until all of the flasks 105 have been shaken out, after which the trolley hoist 30, through the spreader 31, which may now for this purpose, be equipped with a multiplicity of hooks to engage a plurality of pipes with the core bars therein, carries the said pipes and cores back to an 110 assembling point indicated at A, from which they are rolled to the bar puller 33 most convenient, and the bars 9 are withdrawn, the finished pipe rolling towards the rear end of the "bay," upon the tracks 10 to be 115 cleaned, dipped in tar and tested, while the core bars 9 having been withdrawn therefrom, are rolled in the opposite direction or forwardly to the core machine 31 for the making of a new core thereon.

In Fig. 6 of the drawings, there is illustrated a modified form of plan or arrangement of the foundry plant which is within the scope of this invention, the functioning 125 of the various machines and devices being the same, and the various steps in the operations being identical. In this figure, the same reference characters have been applied with the exponent "a" in order to identify the similar parts or machines and de- 130

vices, and it is therefore deemed unnecessary to give more than a cursory description of the same.

The cupola 36^a in this form is located at 5 the end of a runway having spaced rails 34^a extending entirely along the abutting ends of a series of opposed "bays," defined between spaced, upright posts or columns 1^a constituting the structural supports for 10 the roof of the foundry. Mounted on the rails 34^a is a car 38^a similar to the supplemental car 38 of the first described form of plant, the said car 38^a being adapted to receive a multiple-lipped ladle 24^a, and to 15 shift the same to a position beneath the spout 37^a of the cupola for the purpose of charging the same. The ladle is adapted to be swung about a vertical pivot carried by the car, so that the ladle may be turned at 20 right angles to the car, or be shifted at an angle thereto, in order to facilitate the entrance of the molten metal from the cupola into the ladle, as it is sometimes necessary to turn the elongated ladle slightly to prevent the metal from splashing out, especially 25 when there is a heavy head of the metal within the cupola, or when the ladle is nearly full.

The columns 1^a carry overhead tracks 16^a 30 extending throughout the length of each pipe floor across the intervening runway and along the entire length of the opposite pipe floor, and on these tracks are mounted the overhead cranes 17^a having the various 35 hoists described in connection with the first form of the invention; and arranged centrally of each "bay" there is an overhead monorail 29^a passing across the runway for the car 38^a and adapted to carry the trolley hoists 30^a.

The spaced floor tracks 2^a arranged adjacent to the margins of the "bays" are for 40 the cars having the molding machines thereon, and are located so as to allow space for the stacks 12^a of the flask sections, and said tracks 2^a are flanked by the supporting sills 4^a to receive and support the completed flasks 6^a, having the molds therein, in a position transversely of the "bays," after the 45 said molds have been made of the sand from the piles 15^a located between the spaced tracks 2^a, as before. The outer ends of each "bay" (not shown) are provided with the core machines and the core bar pulling machines, as in the first form of the invention, and, as has been stated, the mode of procedure and the steps of the operations are carried out in the same manner. When the 50 car 38^a, having the filled ladle thereon, is shifted opposite the end of the "bay" to be poured, the said ladle is swung about its central pivot 24^a to 90 degrees in order to align the same with one of the overhead cranes 17^a, which has been advanced to a position 55 midway of the runway below, and

the said ladle is then connected to the proper hoists carried by the crane and carried to the pouring position.

The structure of the car for carrying the ladle, and the structure of the ladle per se, 70 has not been described in detail in this application, as the same forms the subject-matter of a companion application filed of even date herewith and entitled "Method of casting pipe or other castings with a trough-type, multiple-lipped ladle."

While two forms of the invention have been shown and described, it will be understood that certain departures from the showing thereof may be resorted to without departing from the spirit of the invention. 80 With an understanding of these two forms, it will be seen that the art of making cast iron pipe or other analogous castings has been materially advanced, and that by the 85 adoption of the method herein employed, a great saving of time and the cost of production may be obtained, and a larger measure of safety to the operatives may be had, the number of steps usually employed in the 90 ordinary method of vertical casting in pits, being reduced. By reason of the multiple-lipped ladle, and the means for quickly and 95 safely handling and carrying the same from the cupola to the point of pouring, the metal 100 may be poured quickly and safely and the surging of the metal, which is so common and so dangerous, while in transit, is eliminated.

What is claimed is:—

1. A foundry plant comprising a plurality of units defined by rows of upright beams, two pairs of spaced rails constituting tracks arranged longitudinally in pairs between the rows of beams and spaced from the same, rows of flasks arranged in longitudinal piles in the spaces between the beams and the pairs of tracks, supports for transversely arranged flasks arranged in the space between the pairs of tracks, a pile or 105 piles of sand also arranged longitudinally in the space between the two pairs of tracks, and overhead means for transferring the flasks from the several rows onto said supports transversely and progressively along 110 and between the tracks as the sand is used in filling the flasks.

2. A foundry plant comprising a plurality of units defined by rows of upright beams, two pairs of spaced rails constituting 120 tracks arranged longitudinally between the rows of beams and spaced from the same, each pair of rails being spaced from each other, longitudinally disposed sills located in the space between the pair of rails, said 125 sills serving as supports for transversely arranged flasks, and molding machines mounted on wheels and movable along the tracks.

3. A foundry plant comprising a plu- 130

- rality of units defined by rows of upright beams, two pairs of spaced rails constituting tracks arranged longitudinally between the rows of beams and spaced from the same, 5 each pair of rails being spaced from each other, longitudinally disposed sills located in the space between the pair of rails, said sills serving as supports for transversely arranged flasks, other sills located at approximately 10 the center of the flasks, means cooperating with said other sills to chock up the center of said flasks, and molding machines mounted on wheels and movable along the tracks.
- 15 4. A foundry plant comprising a plurality of units defined by rows of upright beams, two pairs of spaced rails constituting tracks arranged longitudinally between the rows of beams and spaced from the same, each pair 20 of rails being spaced from each other, longitudinally disposed sills located in the space between the pairs of rails, said sills serving as supports for transversely arranged flasks, other longitudinally arranged sills located at approximately 25 the center of the flasks, a pile or piles of molding sand located in the spaces between the two sets of sills, and molding machines mounted on wheels and movable along the tracks.
- 30 5. A foundry plant comprising a plurality of units defined by rows of upright beams, two pairs of spaced rails constituting tracks arranged longitudinally in pairs between the rows of beams and spaced from the same, 35 rows of flasks arranged in piles in the spaces between the beams and the pairs of tracks, and molding machines mounted on wheels and movable along the tracks.
6. A foundry plant comprising a plurality of units defined by rows of upright beams, two pairs of spaced rails constituting tracks arranged longitudinally in pairs between the rows of beams and spaced from the same, rows of flasks arranged longitudinally in piles in the spaces between the beams and the tracks, a pile or piles of molding sand located in the space between the two tracks, and molding machines mounted on wheels and movable along the tracks.
- 50 7. In a foundry section or unit, a molding machine mounted on wheels to run on tracks, in combination with a traveling crane positioned at right angles to the movement of the molding machine.
- 55 8. A foundry section or unit comprising longitudinal tracks, longitudinally disposed molding machines mounted on wheels shiftable on said tracks and arranged on opposite sides of said section or unit, there being a longitudinal sand pile or piles between the tracks, spaced flask supports between and adjacent to the longitudinal tracks, and means for lifting flask sections from the machines and placing the same transversely between the tracks and on the supports.

9. A pipe foundry comprising a plurality of sections or units having opposite, longitudinally-disposed 2-rail tracks, a molding machine mounted on each track, said molding machines being also arranged longitudinally of the section or unit, longitudinal flask supports located between the said tracks, and overhead hoisting means for placing flask sections on the molding machines and for lifting the same therefrom and placing them transversely upon the supports.

10. A pipe foundry comprising a plurality of sections or units having opposite, longitudinally-disposed 2-rail floor tracks, a molding machine mounted on each track, said molding machines being also arranged longitudinally of the section or unit, longitudinal flask supports located between said tracks, an intermediate longitudinal sill arranged between the supports, means for placing flask sections upon the machines for ramming, lifting the same therefrom and placing them transversely upon the supports, and means for chocking the flasks upon the intermediate sill.

11. A pipe foundry comprising a plurality of sections or units having opposite longitudinally-disposed 2-rail floor tracks, a molding machine mounted on each track, said molding machines being also arranged longitudinally of the section or unit, flask supports located between said tracks, overhead means for placing flask sections on the molding machines and for lifting the same therefrom and placing them transversely upon the supports to be rammed, opposite overhead tracks for supporting said overhead means arranged longitudinally of the section or unit and adjacent to the walls thereof, a monorail arranged above and between the overhead tracks, and a trolley having lifting means and mounted on the monorail for transferring cores to the transversely arranged flask sections and for removing pipes and core bars therefrom.

12. A pipe foundry comprising a plurality of sections or units having opposite longitudinal floor tracks, molding machines mounted to move along said tracks, transverse molds supported between the tracks, a monorail located above and between the tracks, a trolley having lifting means and mounted to move along the monorail, said monorail being in the form of a loop traversing two or more units to serve the same from a single core making machine.

13. In a pipe foundry, the combination of an overhead, traveling crane movable longitudinally thereof and having lifting means thereon, flask supports arranged longitudinally of the foundry and beneath the crane, spaced tracks between the supports and the longitudinal walls of the foundry, longitudinally movable molding machines mount-

ed on said tracks, transfer tracks located at one end of the foundry and at right angles thereto, a cupola located on the opposite side of the transfer tracks, a transfer car mounted on the transfer tracks and adapted to be shifted in front of the cupola, and a supplemental car mounted on the transfer car and movable transversely thereon, said supplemental car having means for supporting a ladle.

14. A pipe foundry having overhead tracks, a traveling crane movable thereon and equipped with lifting means, a cupola located at one end of the foundry, transfer tracks arranged transversely of the crane tracks and beneath the overhanging ends thereof, a transfer car movable on the transfer tracks and adapted to receive a ladle from the crane and to place the same before the cupola for filling and to return the ladle to the crane when filled, floor tracks adjacent to each longitudinal wall of the foundry, a molding machine mounted on each track, flask supports arranged between the tracks, a longitudinal monorail supported above the crane and intermediate the ends thereof, a trolley having lifting means and adapted to travel on said monorail to convey cores from a core machine to any of the flasks or to convey pipes with the core bars therein to a point for extraction of the core bars.

15. In a foundry section or unit, the combination of overhead tracks, a traveling crane movable thereon and having lifting means, transfer tracks arranged transversely of the first-named tracks and beneath the overhanging ends thereof, a transfer car movable along the transfer tracks, a cupola located on the opposite side of the transfer tracks, and a supplemental car mounted on the transfer car and movable transversely

thereof, said supplemental car having means for supporting a ladle.

16. A pipe foundry having overhead tracks, a traveling crane movable thereon and equipped with lifting means, a cupola located adjacent to one end of the foundry, transfer tracks arranged transversely of the crane tracks and beneath the overhanging ends thereof and in front of the cupola, a transfer car located on the transfer tracks and adapted to receive a ladle from the crane, and to place the ladle before the cupola for filling and to return the ladle to the crane when filled.

17. A pipe foundry having overhead tracks, a traveling crane movable thereon and equipped with lifting means, longitudinal floor tracks, molding machines mounted to move along said floor tracks, a monorail located above and between the overhead tracks, and a trolley having lifting means and adapted to move along the monorail independently of the crane.

18. A foundry plant comprising a plurality of units defined by rows of upright beams, two pairs of spaced rails constituting tracks arranged longitudinally between each row of beams and spaced from the same, molding machines mounted on wheels and shiftable along the tracks, overhead tracks mounted on said beams, and a travelling crane movable on the overhead tracks above the molding machines and having a transversely movable carriage with hoisting means, whereby one crane takes care of the molding machines movable along the tracks below.

In testimony, that I claim the foregoing as my own, I have hereto affixed my signature.

JAMES R. MCWANE.
